FRANKFURTER PACKAGE UNIT AND PROCESS FOR COOKING FRANKFURTERS

Jacob S. Richman, 43 S. 19th St., Philadelphia, Pa.

Filed May 2, 1956, Ser. No. 582,148

5 Claims. (Cl. 99—174)

The present invention relates to a frankfurter package unit, and more particularly to a frankfurter package unit in which a novel form of frankfurter, preferably deposited within a suitable bun may be cooked, and to a process for cooking frankfurters within a package unit.

The dispensing of frankfurters through vending machines and the like has long presented a difficult problem, which until the advent of the present invention has not been satisfactorily resolved. Thus, the dispensing of cooked frankfurters from a vending machine requires that the frankfurter be heated from a refrigerated condition to a condition in which it is palatable (such as to a temperature of the order of 160° F. or more) within a relatively short period of time, such as a period of time of the order of fifteen or so seconds. Moreover, the frankfurter, and if a roll or bun is present, then the roll or bun also, must be kept absolutely free from contamination with the outside or surrounding atmosphere.

This invention has an object the provision of a frankfurter package unit in which a frankfurter, and if desired, a roll or bun, may be positioned, and may be cooked or heated to a palatable temperature within a short period of time without exposure to contamination arising from the surrounding atmosphere or environment.

The present invention has as another object the provision of an attractive and relatively inexpensive container for a frankfurter and bun or for other like comestibles.

This invention has as a different object the provision of a process for the cooking or heating of frankfurters or similar comestibles without exposing such frankfurters or comestibles to their environment.

Other objects will appear hereinafter.

For the purpose of illustrating the invention there is shown in the drawings a form which is presently preferred; it being understood, however, that this invention is not limited to the precise arrangements and instrumentalities shown.

Figure 1 is a perspective view of the frankfurter package unit of the present invention in which a frankfurter of the present invention and a roll are retained within a wrapper.

Figure 2 is a view of the wrapper portion of the frankfurter package unit of the present invention in unrolled or open disposition.

Figure 3 is an exploded view of the frankfurter and bun portion of the frankfurter package unit of the present invention.

Figure 4 is a diagrammatic view showing how a frankfurter of the present invention disposed within a bun and carried within the frankfurter package unit of the present invention may be readily cooked between electrodes without removal of the frankfurter from the package.

Referring to the drawings, the frankfurter package unit of the present invention is designated by the numeral 10. Such frankfurter package unit 10 includes a folded sealed wrapper 12, a frankfurter 14, and may include a conventional open-ended frankfurter bun 16. In addition

2

to the foregoing, additional elements may be present within the frankfurter package unit 10, such as an envelope containing a condiment, such as mustard or ketchup, and/or a paper napkin.

5 In the illustrated embodiment the wrapper 12 comprises three elements securely joined together, such elements being aluminum foil strips 18 and 20 and intermediate plastic strip 22. As shown in the drawings, the aluminum foil strips 18 and 20 are bands of relatively thin elemental aluminum metal which are lappingly joined along one side portion thereof to a mating side portion of the plastic strip 22. Plastic strip 22 is preferably formed from a flexible non-conducting plastic, such as for example polyethylene or the like, and preferably is transparent permitting visual observation of the frankfurter 14 and bun 16. The securement of the aluminum foil strips 18 and 20 to the plastic strip 22 may be accomplished by adhesives or by other means known to the art.

20 In place of the illustrated embodiments, other securement arrangements between the aluminum foil strips and the plastic strip are possible, namely securement arrangements wherein the plastic strip is in the form of a tongue and is sandwiched between the laminae of a laminated aluminum foil. Where laminated aluminum foil is used, the adhesive, if any, joining the laminae should be a conductor.

25 The frankfurter 14 of the present invention should be in the form shown particularly in Figure 3. Thus, the frankfurter 14 is a cylindrical sausage element whose ends 24 and 26 have been trimmed of the casing, if present, and the derma or thickened outer portion of the frankfurter for an appreciable extent, such as of the order of one-half inch or so to expose the pulp or inner meat portion of the frankfurter. While trimming of the cylindrical surface formed about the longitudinal axis of the frankfurter is not essential, but is preferable; trimming of the derma from the ends generally normal to the longitudinal axis of the frankfurter is essential to the frankfurter construction of the present invention. The portion of frankfurter 14 intermediate ends 24 and 26 is not trimmed and may be provided with a casing, and is provided with the derma or relatively thick compressed or characteristic outer epithelial frankfurter portion. Thus, by "derma" as used herein is meant the hardened meat portion of the frankfurter which forms beneath the casing during the smoking process in which the frankfurter is formed, and which remains if the casing is peeled off.

30 40 45 50 55 The bun 16 should be of substantially the same length or slightly shorter than the frankfurter 14. The bun 16, as will be more fully explained hereinbelow, provides support for the frankfurter 14 when the latter undergoes compression in being cooked in accordance with the process of the present invention.

55 In the assembled package unit 10 the wrapper 12 encompasses the frankfurter 14 and bun 16 with the ends 24 and 26 of the frankfurter 14 juxtaposed to their respective adjacent aluminum foil strips 18 and 20, while the aluminum foil strips 18 and 20 are in non-conducting relationship in respect to each other, being separated by the plastic strip 22. The aluminum foil strips 18 and 20 of the package unit 10 may be sealed or closed by the use of heat and/or adhesives or by other means readily understood by one skilled in the art.

60 65 70 75 The cooking of frankfurter 14, which may be in a refrigerated state, as at a temperature of about 40° F., is accomplished by placing the frankfurter package unit 10 between electrodes 28 and 30 in the manner shown in Figure 4 and applying to the electrodes an inwardly directed force (in the direction of the arrows shown in Figure 4. The application of such force axially com-

presses the frankfurter 14, the bun 16 acting as a reinforcement or support therefor during such compression. When electrical current is passed between electrodes 28 and 30, such current passes through the aluminum foil strips 18 and 20 and thence through the trimmed ends 24 and 26 of frankfurter 14. Inasmuch as plastic strip 22 is a non-conductor, the flow of current through it or along its surface is obviated.

The present invention may be embodied in other specific forms without departing from the spirit or essential attributes thereof and, accordingly, reference should be made to the appended claims, rather than to the foregoing specification as indicating the scope of the invention.

I claim:

1. A frankfurter package unit comprising a frankfurter axially confined in a wrapper, said frankfurter having its pulp portion exposed at both ends at right angles to its longitudinal axis within said wrapper, said wrapper consisting of sealed end portions formed of a flexible metallic conducting material secured at opposite end portions to a central non-conducting wrapper material, the trimmed ends of the frankfurter being juxtaposed to the sealed metallic conductor ends of the wrapper whereby said frankfurter may be cooked without removal from said wrapper by insertion of the entire package intermediate a pair of electrodes and applying electrical current through the electrodes in sufficient amount to heat the frankfurter without the electrodes perforating said wrapper.

2. A frankfurter package unit in accordance with claim 1 in which the flexible metallic conducting material at the sealed end portions of the wrapper comprises aluminum foil, and the central non-conducting wrapper material comprises a transparent plastic.

3. The process of heating a cold frankfurter having its pulp portion exposed at both ends at right angles to its longitudinal axis which comprises positioning a cold frankfurter contained within a wrapper having conducting elements at both ends juxtaposed to the exposed pulp

portion at the ends of the frankfurter with the ends separated by a non-conductor, inserting said wrapper and frankfurter intermediate a pair of electrodes with the conducting ends of said wrapper being juxtaposed to said electrodes, actually compressing said frankfurter while it is positioned between said electrodes by inwardly moving at least one of the electrodes without perforating said wrapper, and applying electrical current through the electrodes in sufficient amount to heat the frankfurter.

4. The process of heating a cold frankfurter without the exposure of such frankfurter to the atmosphere which comprises axially confining a cold frankfurter having its pulp portion exposed at both ends at right angles to its longitudinal axis within a longitudinal wrapper having conducting materials secured at opposite end portions and separated by a non-conductor center, juxtaposing the exposed pulp ends of said frankfurter to said end portions comprising conducting materials, inserting said wrapper and frankfurter intermediate a pair of electrodes, juxtaposing the conducting end portions to the electrodes, compressing said frankfurter intermediate said electrodes without perforating said wrapper, and applying electrical current through the electrodes in sufficient amount to heat the frankfurter.

5. A process in accordance with claim 4 in which the frankfurter is axially disposed within a longitudinal bun.
